UNITED STATES PATENT OFFICE.

OLE K. OPPEN, OF CHICAGO, ILLINOIS.

CYLINDER FOR WASHING-MACHINES.

1,157,121.

Specification of Letters Patent. Patented Oct. 19, 1915.

Application filed May 17, 1915. Serial No. 28,690.

To all whom it may concern:

Be it known that I, OLE K. OPPEN, a citizen of the United States, residing at Chicago, in the county of Cook and State of Illinois, have invented certain new and useful Improvements in Cylinders for Washing-Machines; and I do declare the following to be a full, clear, and exact description of the invention, such as will enable others skilled in the art to which it appertains to make and use the same.

My invention relates to improvements in washing machines, and more particularly to cylinders to be rotated in receptacles of water or other cleaning liquid.

The object of the invention is to improve upon the general construction of such cylinders to such an extent as to provide a device which although being of comparatively simple construction, will be extremely efficient in operation.

With this general object in view, the invention resides in certain novel features of construction and in the unique combinations of parts hereinafter fully described and claimed.

In describing the invention, I shall refer to the accompanying drawings wherein:

Figure 1 is an end view of a cylinder constructed in accordance with my invention, showing the same disposed for use in a receptacle, the latter being shown in vertical section; Fig. 2 is a side elevation of the cylinder with the receptacle in section; Fig. 3 is a vertical transverse section as seen along the plane indicated by the line 3-3 of Fig. 2; and Fig. 4 is a horizontal section taken substantially along the line 4-4 of Fig. 3.

In these drawings wherein like reference characters designate corresponding parts throughout the several views, 1 indicates broadly the washing cylinder wherein resides the gist of the present invention. The cylinder 1 is composed of a pair of end walls 2, and a plurality of slats or the like 3 leading longitudinally from one end wall 2 to the other, these slats constituting the curved wall of the cylinder. At points spaced circumferentially around the same, this curved wall is provided with gaps 4 disposed longitudinally, a trio of such gaps being shown in the present application although any preferred number could well be provided.

The cylinder 1, when applied to use, is to be rotated only in the direction indicated by the arrow in Figs. 1 and 3 of the drawings,

the opposite edges of the gaps 4 being therefore hereinafter termed the front and rear edges thereof. Extending inwardly from the front edges of these gaps and disposed at substantially right angles to the curved wall of the cylinder, is a trio of clothes lifting flanges 5, while projecting inwardly from the rear edges of said gaps are the gratings 6 which may be in the form disclosed in the drawings or of any other preferred design for accomplishing the best results. Leading rearwardly from the inner edge portion of each flange 5 and secured thereto at a predetermined point, is a dash board 7 which continues to the immediately adjacent grating 6, it being secured to the latter at a point spaced outwardly toward the curved wall of the cylinder from the aforesaid point at which it is secured to the flange 5.

The entire cylinder 1 is disposed in a suitable tub or the like 8 preferably mounted on legs 9, in which position it may be rotated in the direction indicated by the arrow in the drawings by the provision of the crank 10, the pulley 11, or by any other preferred motive power. In operation, the tub 8 is partially filled with water until the level thereof is approximately even with or slightly above the upper edge of the lowermost clothes lifting flange 5, whereupon the clothes to be washed are deposited in the cylinder 1, care being taken to only approximately half fill said cylinder, whereby only the two lowermost lifting flanges 5 will come into action upon the first fraction of a revolution of the cylinder. The cylinder 1 is now rotated, the result of this movement being that the clothes within the cylinder are raised to the upper side thereof by the lifting flanges 5, whereupon they will slide from these flanges and will fall onto the dash boards 7 as the latter approach positions at the lower side of the cylinder. From these dash boards 7, the clothes slide rearwardly onto the slats 3, upon which slats they are now moved rearwardly by the streams of water forced through the gratings 6, until they come in contact with other flanges 5, whereupon the same operation is repeated.

It has been found by actual tests, that a cylinder constructed in the manner set forth and operating as described, will effectively remove all dirt and the like from clothes with comparative ease. The efficiency of the machine depends not only upon the

falling of the clothes from the several clothes lifters onto the dash boards, but upon the fact that they are suddenly forced rearwardly against said lifters by the jets of water entering through the gratings or the like. In addition to these jets producing a rinsing effect upon the articles being washed, they effectively seat the same upon the lifters 5, whereupon the latter may actuate more effectively than they could otherwise.

Although the cylinder 1 may be provided with any preferred means for allowing the clothes or the like to be deposited therein, the end walls 2 are preferably made sectional as shown in the drawings, and two of the dash boards 7 are split longitudinally, the two portions of one of said boards being hingedly connected, while any preferred type of latch means is provided for connecting such portions of the other board. By this construction, the latching means may be released whereupon a portion of the cylinder wall may be raised, thereby readily allowing access into said cylinder.

From the foregoing description, taken in connection with the accompanying drawings, it will be evident that although extremely simple construction has been provided for carrying out the object of the invention, the complete machine will be highly efficient in operation.

Particular emphasis is laid upon the provision of the circumferentially spaced clothes lifters and the water inlets disposed forwardly from said lifters and delivering

toward the same; upon these features in combination with the circumferentially spaced dash boards leading forwardly from the several water inlets to the clothes lifters, and upon the general construction of the entire device.

In the drawings, certain specific details of construction have been shown for accomplishing probably the best results, and in the foregoing such details have been described, but it will be evident that I need not be limited thereto otherwise than to the extent to which the appended claim restricts me.

I claim:—

A washing cylinder to be rotated in one direction in a receptacle of water and having a plurality of circumferentially spaced longitudinally extending gaps in its curved wall, longitudinally disposed lifting flanges extending inwardly from the front edges of the gaps and lying substantially at right angles to said curved wall of the cylinder, gratings extending inwardly from the rear edges of the gaps, and dash boards leading rearwardly from predetermined points on the flanges to the gratings.

In testimony whereof I have hereunto set my hand in presence of two subscribing witnesses.

OLE K. OPPEN.
